GUSTAVUS A. SCHLECHTER, Inventor

By his Attorney *J. H. Newark*

UNITED STATES PATENT OFFICE.

GUSTAVUS A. SCHLECHTER, OF READING, PENNSYLVANIA.

DESIGN FOR A BADGE.

SPECIFICATION forming part of Design No. 22,777, dated September 12, 1893.

Application filed May 24, 1893. Serial No. 475,378. Term of patent 7 years.

To all whom it may concern:

Be it known that I, GUSTAVUS A. SCHLECHTER, a citizen of the United States, residing at Reading, in the county of Berks, State of Pennsylvania, have invented a new and original Design for a Badge, of which the following is a specification.

Figure 1 shows the main face or obverse of my design and Fig. 2 the reverse.

10 The design consists of two distinctive elements, namely the head piece *a* and the pendant *b*.

15 The leading features of the design consist first of the representation of a small portion of a clock dial with a hand (or hands) holding a goblet appearing below the hour figures and ornamentally interwoven letters above the same as shown. This forms the obverse of the head piece. Second the ornamentation 20 upon the reverse side of the head piece which consists mainly of a spray of forget-me-nots around the stem of which is wound a ribbon

the flowing ends of which partly inclose the spray of forget-me-nots and provide a convenient surface for any desired inscription. 25 Third the pendent portion *b* of my complete design representing an elk's tooth upon the face of which and midway between the head piece and the end of the pendant appears in relief the representation of an elk's head with 30 spreading antlers.

What I claim is—

1. The design for a badge substantially as shown and described.
2. In a design for a badge as herein shown, 35 the obverse as set forth.
3. In a design for a badge as herein shown, the reverse as set forth.

In testimony whereof I affix my signature in presence of two witnesses.

GUSTAVUS A. SCHLECHTER.
